CLOSURE APPLYING MECHANISM

Robert J. Stewart and Henry H. Franz, Baltimore,
Md., assignors to Crown Cork & Seal Company,
Inc., Baltimore, Md., a corporation of New York

Application March 4, 1939, Serial No. 259,898

7 Claims. (Cl. 226—84)

The present invention relates to closure applying mechanisms.

In closing bottles or other containers with a cap including a skirt which must be molded or bent about a locking ring upon the mouth of the container, it is essential that the mouth of the container bear firmly upon the lower surface of the body wall of the cap, and that the upper surface of the cap be firmly in contact with the pressure foot included in the capping mechanism, prior to the operation of molding the skirt about the locking ring.

For example, if a container is slightly shorter than standard, and no means is provided to hold such container in the position described above, the skirt of the cap would not be properly molded about and upon the locking ring of the container.

Numerous arrangements, usually termed "compensating mechanisms," have heretofore been provided to hold the container in the proper position referred to above with respect to the capping head, and regardless of whether the container is of standard dimensions. However, all such prior mechanisms are subject to the objection that compensation is performed during the capping movement of the capping head with respect to the container and, naturally, when a capping head moves with sudden force against a container, the container is apt to be damaged.

An important object of the present invention is to provide a closure applying mechanism of such construction that each container will be positioned at the proper height with respect to the mechanism before the capping action takes place.

Another object of the invention is to provide a closure applying mechanism of such construction that capping heads of various types may be readily and interchangeably carried thereby.

In capping some types of containers, particularly milk bottles, each bottling plant may use two or more different types of closures upon bottles. In order that a different capping machine will not be required for application of each type of cap, it is desirable that the capping mechanism be of such construction that different types of capping heads may be readily mounted upon the same.

The present invention includes an arrangement whereby different types of capping heads will be firmly and securely supported upon the capping mechanism by readily releasable securing means, enabling one type of capping head to be quickly removed and replaced by another type.

Other objects and advantages of the invention will be apparent from the following specification and drawings, in which drawings:

Figure 1 is a longitudinal vertical sectional view through a machine for filling and closing

milk bottles and including a capping mechanism constructed in accordance with the present invention.

Figure 2 is a horizontal sectional view on the line 2—2 of Figure 1 or the line 2—2 of Figure 4.

Figure 3 is a diagrammatic view, in side elevation, illustrating the cycle of operation of the compensating structure of the invention.

Figure 4 is a side elevation of the compensating structure, with a portion in vertical section.

Figure 5 is a horizontal sectional view of the valve included in the compensating structure, the section being on the line 5—5 of Figure 4.

Figure 6 is a top plan view of the capping mechanism.

Figure 7 is a vertical sectional view on the line 7—7 of Figure 6.

Figure 8 is a horizontal sectional view on the line 8—8 of Figure 9.

Figure 9 is a view, generally in vertical section, showing the compensating structure and a form of capping mechanism, and

Figure 10 is a view similar to Figure 9 but showing the capping mechanism in another position.

The filling machine illustrated in Figure 1 may be generally described as comprising a table or base casing 20 having a milk reservoir 21 positioned above the same for rotation. During rotation of the reservoir, bottles successively positioned upon the vertically reciprocable supports 22 will be filled by means of the filling heads 23 described in our continuation-in-part application for Methods and apparatus for filling, Serial No. 341,744, filed June 21, 1940. Filled bottles are removed from the supports 22 by a rotatable transfer dial carried on a vertical shaft 24, which dial positions successive bottles upon bottle platforms 25 for movement through the closure applying or capping mechanism of the present invention.

The capping mechanism includes a normally stationary post 30 and a hollow column 31 having a gear 32 fixed to its lower portion and suitably rotated through a speed reducing mechanism 33 by a motor, not shown. The hollow column 31 is journaled upon suitable bearings as shown in Figure 1 and extends up about the post 30 through an upward extension 35 of the base casing 20. A supporting sleeve 36 is secured to the column 31 and extends downwardly about the upward projection 35 of the base 20. At its upper end the non-rotatable post 30 rotatably carries a capping head supporting structure 40 including a depending sleeve 41. The depending sleeve 41 is keyed to the rotatable column 31 so that the entire structure 40 will rotate with this column.

Each bottle supporting platform 25 of the capping structure includes a depending sleeve 43

which is preferably rectangular in cross-section as shown in Figure 2 and is vertically slideable upon a post 44, the lower portion of the post being welded or otherwise secured to a flange or table 45 at the lower end of the base sleeve 38. The extreme lower end of each post 44 preferably extends slightly below the lower surface of flange 45 to form cams for a purpose hereinafter set forth. In order that the downward movement of each platform 25 may be limited so that in its downward limit position the upper surface of the platform will be flush with the upper surface of the worktable of the machine, each upright or post 44, as shown in Figure 4, has a relatively large set screw 48 threaded in its upper end. By this arrangement, upon removal of a platform 25 from its guiding upright 44, the set screw 48 may be so adjusted as to give the platform 25 a desired downward limit of movement. A locknut may be provided on each set screw 48 to hold the latter in adjusted position. It will be noted from the above that the platforms 25 may be readily removed from the uprights 44 for cleaning or other purposes.

As best shown in Figures 1, 6 and 9, the capping head supporting structure 40 includes a flange or tablelike portion 50 extending from the upper end thereof, which portion includes a depending skirt 51 suitably reinforced by ribs 52 extending from the sleeve 41. The flange portion 50 has slots or pockets 55 (Figures 6, 7 and 8) circumferentially spaced about its periphery which slots are adapted to receive various types of capping heads. In order to conform to the present mechanism, each capping head would be supported in a bracket such as indicated by the numeral 56, the side and rear edge portions of which will closely fit a pocket 55, and the bracket also including an upper lateral flange 57 (Figure 7) and a lower lateral flange 58, the upper flange being adapted to rest upon the upper surface of the supporting structure flange 50 and the lower flange 58 being adapted to closely engage the under portion of flange 50. Flanges 57 and 58 have apertures 60 therein adapted to be aligned with a bore 61 in the supporting structure flange 50, and a pin 62 is adapted to be inserted through the upper end of these aligned apertures to prevent a bracket 56 and the capping head carried thereby from moving laterally with respect to the pocket 55. Each pin 62 is preferably provided with a downwardly facing shoulder adjacent its upper end to limit its downward movement to the aligned apertures. It will be noted that the brackets 56 may be inserted in the pockets 55 by moving the latter radially into the pockets and then inserting the pins 62. With the pins inserted, the flanges 57 and 58 will prevent all movement of the bracket with respect to the body flange 50.

The capping heads disclosed in the present application for the purpose of illustrating the operation of the present invention are of the type described in the patent to George W. Booth, for Capping machine, No. 1,956,208, April 24, 1934, which heads are particularly intended for applying to bottles a cap blank of hat-shaped form as indicated at C in position A of Figure 9 and forming this hat-shaped blank into a skirted closure C' of the type shown in position C of Figure 9. Referring to Figures 9 and 10, each capping head includes a capping chamber 70 at its lower end in which is positioned a throat ring 71 and a presser foot 72, the presser foot normally having its lower surface substantially flush with the low-

er edge of the throat ring 71 as shown in position A of Figure 9 and in Figure 10. A cap blank supply chamber 73 is secured to each capping head 69 and a slideway 74 beneath each cap blank supply chamber 73 has a pusher 75 mounted for reciprocation therein to move the lowermost cap blank in the supply chamber 73 into the capping chamber 70, as described in Patent No. 1,956,218, issued April 24, 1934, to George J.

10 Huntley and Harry A. Rau for Capping head.

More specifically, each capping head 69 includes a cylindrical body portion 78 which fits and is vertically movable in a vertical bore 79 of the bracket 56, vertical keys 80 being provided 15 as shown in Figure 8 to hold the cylindrical body 78 against rotation with respect to the bracket 56. The cylindrical body 78 includes a large central bore 81 having its upper end closed by a block or fitting 82 threaded in the bore. A relatively strong coil spring 83 is positioned in the large bore 81 with its upper end bearing against the lower surface of the block 82 and its lower end bearing upon the enlarged head 84 of a spindle 85. The lower surface of spindle head 25 84 normally rests upon an annular shoulder 86 provided adjacent the lower end of the bore 81. The lower end of spindle 85 bears upon the upper portion 87 of presser foot 72, which portion is slightly flanged to bear upon a ring-like plate 30 88 supported upon the upper edge of the throat ring 71. As is described in said Huntley and Rau patent, the plate 88 has upwardly extending pins 89 circumferentially spaced about the same which pins extend through apertures in the upper wall 35 of the capping chamber 70 and have a flat ring 90 secured to their upper ends which ring, upon upward movement of the capping head, is adapted to contact with the lower surface of the capping head supporting structure, in the present 40 instance, the supporting bracket 56. The throat ring 71 includes a shoulder 92 at its upper end which rests upon a ring 93 bearing upon a coil spring 94, the lower end of coil spring 94 bearing upon a second ring 95 secured in the side wall of 45 the capping chamber.

A ledge 96 surrounds the capping chamber 70 just below the normal position of the presser foot 72, and an opening 97 is provided at the portion of the chamber 70 adjacent the slideway 74 50 through which cap blanks C may be moved to the ledge 96 by pusher 75.

The cap blank supply chamber 73 is of tubular form and extends parallel with the tubular body 78 of the capping head so that a stack of cap 55 blanks may be positioned in the chamber 73. The stack of caps is supported upon feed devices 99 circumferentially spaced about the chamber, these devices being of such form that, as described in said Huntley and Rau patent, the lowermost cap of the stack will be dropped at suitable intervals to rest upon the upper surface of the pusher 75 as shown in position A of Figure 9.

The pusher 75 is adapted to be reciprocated in the slideway 74 by means of a pair of bell cranks 65 100, one at each side of a capping head as shown in Figure 6, these bell cranks being pivoted upon a pin 101 extending through the portion of the bracket 56 between the bore 79 of the latter and the cap blank supply chamber 73. Each bell crank 100 includes a relatively short arm 102 70 which carries a roller positioned between a pair of vertically spaced lugs 103 on the corresponding outer surface of the chamber 73. The other and relatively long arm 104 of each bell crank 100 is pivotally connected to a link 105, the outer

end of the link being pivotally connected to the corresponding side of the pusher block 75 by means of a pin 106 extending from the corresponding side of the pusher block and through a horizontal slot 107 in the adjacent side wall of the slideway 74.

As is described in said Huntley and Rau patent, with the elements of the capping head in the relation shown in the position A in Figure 9, that is, with a bottle B just moving upwardly toward the capping head, and with the pusher block 75 in the inward position illustrated, and with a cap blank C resting upon the upper surface of the pusher block, the operation of the capping head will be generally as follows. Continued upward movement of the bottle will first raise the entire capping head upwardly to the position shown in Figure 10 with respect to the supporting bracket 56. Because of the fact that the cap blank supply chamber 73 will move upward with the body cylinder 78 of the capping head, the lower lug 103 at each side of the cap supply chamber 73 will act upon the shorter arm 102 of bell crank 100 to swing the latter in a clockwise direction (Figures 9 and 10,) thereby swinging the longer arm 104 of each bell crank to the right or outwardly so that the pusher block 75 will be moved to the position shown in Figure 10. This movement of the pusher block will permit the cap blank C shown resting on the upper surface of the pusher block in position A of Figure 9 to drop upon a ledge in the slideway 74 so that the cap blank will be positioned directly in front of the tongue 75a of the pusher block as shown in Figure 10. Continued upward movement of the bottle as shown in position C of Figure 9 will force the presser foot 72 upwardly and since the cap blank C already within the cap chamber is clamped beneath the lower surface of the presser foot and the mouth of the bottle, the edge or rim portion of that cap blank will be bent downwardly to seal and cap the bottle as shown at position C.

When the capped bottle then descends, the capping head 69 will be held raised for a short interval of time by reason of the fact that a roller 110 carried by an upwardly extending shank of block 82 will ride upon a cam 111 carried by a plate 112 fixed to non-rotatable post 30, all as described in our application filed March 4, 1939, Serial No. 259,897, entitled Capping mechanism, Patent No. 2,260,349, issued October 28, 1941. As described in said application, the roller 110 will eventually ride off the far end of cam 111 so that the entire capping head will return to the position shown in position A in Figure 9. During such downward movement, the upper lugs 103 of the cap blank supply chamber 73 will bear upon the shorter arms 102 of the bell cranks 100 so as to swing the bell cranks in a counter-clockwise direction with respect to Figures 9 and 10, thereby moving the pusher block 75 inwardly so that the cap blank C shown positioned in front of the pusher block tongue 75a in Figure 10 and in position C of Figure 9 will be moved inwardly and upon the capping chamber ledge 96 to be positioned beneath the presser foot 72 as shown in position A of Figure 9, while another cap blank C will drop upon pusher 75 as also shown in position A of Figure 9.

In order to raise the bottle supporting platforms 25 from the level at which bottles are placed thereon and then permit the platforms to again return to the level at which the bottles are removed therefrom, a cam 120 is provided

about the lower portion of the capping mechanism. As best shown in Figure 2, the cam 120 is of generally arcuate form in plan elevation and each end 121 of the cam is pivoted upon a stud 122. One stud 122 is carried by a lug 123 secured to a post 124 projecting upwardly from the base table 20 of the machine, while the other stud is carried by a lug 123a projecting from the hollow standard which encloses the transfer dial shaft 10 24.

Referring to Figures 2, 4 and 9, substantially intermediate its length the cam 120 is provided with a lateral extension 126 which bears upon a plunger stem 127 projecting upwardly from a cam control casing 128. As best shown in Figures 4 and 9, the plunger stem 127 extends through a cap 129 which closes the upper end of a vertical bore 130 in the casing 128, the lower end of the plunger stem resting upon a ball 15 mounted in a plunger 131 which is urged upwardly by a coil spring 132. The coil spring 132 is sufficiently strong to urge the cam 120 upwardly. As illustrated in Figures 4 and 5, the portion of the bore 130 below the plunger 131 opens to a 20 valve chamber 135 which, in turn, communicates with a vertically extending liquid reservoir 136. A valve device 137 controls flow of the liquid between the reservoir 136 and the valve chamber 135 and thereby likewise controls the flow of liquid with respect to the plunger chamber or bore 130. The valve device 137 includes a stem 138 extending through the lower end of the reservoir 136 and to the exterior of the casing 128, a packing 139 being provided about the outer portion of the stem to prevent leakage. The inner end of stem 138 is enlarged as indicated at 140, the enlarged portion 140 having a sliding fit with the bore 141 extending between valve chamber 135 and reservoir 136. A series of small ports 30 142 is provided in the enlarged portion 140 extending axially with respect to the valve stem. The extreme end of stem 138 is further enlarged to provide a poppet valve 143 adapted to seat upon a seat portion 144 of the bore 141. The extreme inner end of valve stem 138 is also provided with a stub end bore 145 having radially extending passages 146 opening therefrom to a circumferential groove 147 extending about the stem between the enlarged portion 140 and the inner face of the poppet valve 143, so that the axially extending bores 142 will always be in communication with the central or stub end bore 145. A seat 148 is formed in the outer end of the central bore 145 on which a ball check valve 50 149 is adapted to be held seated by a spring 150 positioned within a cage 151 mounted upon the outer face of the poppet valve 143. The poppet valve 143 is urged to closed position by a coil spring 152 positioned between the outer face of the valve and the closure plug 153 of valve chamber 135. The spring 152 also of course urges the stem 138 to an outward position with respect to the control casing 128, that is, to the left in Figures 4 and 5.

55 A trip lever 160 (Figures 3 to 5) is pivoted upon the control casing 128 with a vertical arm 161 of this lever extending downwardly adjacent the outer end of the valve stem 138, the other and horizontal arm 162 of the lever carrying a roller 163 which the lower ends of the posts of the uprights 44 are adapted to contact so as to swing the lever 160 in a counter-clockwise direction with respect to Figures 3 and 4. The vertical arm 161 of lever 160 carries a set screw or 60 stud 165 which is adapted to contact with the

70

75

outer end of stem 138. The set screw 185 is held in adjusted position by means of a locknut as shown in Figure 5.

It will be observed from the above that when, as shown in Figure 4, the lower end of one of the uprights 44 is contacting with the roller 163, the vertical arm 161 of lever 80 will be in the right hand position shown in Figure 4 with the result that the reservoir 136 will be in communication with the lower end of plunger chamber 130 through open valve device 137, so that they may be a free flow of liquid between these two chambers. At such time cam 120 will be urged upwardly by the spring 132, but will also be free to be moved downwardly as hereinafter described.

It will be noted that from the diagrammatic showing of Figure 3 that the roller 163 of trip lever 160 is positioned at a point past the highest point of cam 120 so that the position of the trip lever 160 will be controlled by the upright or cam surface 44 of a bottle supporting platform 25 which has already moved past the high point of the cam.

It will be understood that instead of the lower ends of the uprights 44 being used as the cams to actuate trip lever 160, the ring or flange 45 which, in the present construction, joins and supports the uprights 44, may have suitable cam surfaces formed thereon, one for each bottle supporting platform 25. In any event, the leading and trailing edges of this cam will be inclined as shown in Figure 4.

The operation of the cam 120 and the control mechanism within the casing 128 is as follows: At the moment that a bottle is positioned upon a bottle supporting platform 25 by the transfer spider on shaft 24 (Figure 1), that platform 25 will, by its own weight, be in lowered position, that is, the lower surface of the platform will be resting upon the head of the set screw 48 (Figure 4) provided at the top of the corresponding post 44. At this moment, the upper surface of the platform will be flush with the table surface upon which the bottle is being moved by the transfer spider. The rotation of the column 34 which carries the bottle supporting platforms support 36 will immediately thereafter cause the roller 26 associated with that platform 25 to move upon the leading end 120a of the cam 120 as indicated at the left hand portion of Figure 2 and at the right hand portion of Figure 3. As shown in Figures 3 and 9, the entrance portion 120a of cam 120 is the lower portion of an incline 120b of cam 120 so that the bottle platform 25 will immediately begin to raise to a position corresponding to position A of Figure 9, thereby causing the mouth of the bottle B to move upwardly into the capping chamber 70 of the capping head 69 above the platform.

The bottle will continue to rise as the roller 26 continues to ascend incline 120b and until the roller 26 reaches the level dwell 120c at which time the mouth of the bottle will contact with the undersurface of the cap blank C as shown in Figure 10. Should the bottle be of slightly more than standard height, the weight of the capping head is sufficient (and spring 83 is also of such strength) that a force will be created to act through the bottle B and the bottle platform 25 to force cam 120 and the plunger 131 downwardly against the action of plunger spring 132 and the liquid within the plunger chamber 130. Liquid will thus be forced out of the plunger chamber and through the open poppet valve 137 into the reservoir 136.

As shown in Figure 3, at the time that the roller 26 of one bottle platform 25 is moving across the greater portion of the level dwell 120c, the lower end of the preceding bottle platform upright 44 is bearing upon the trip lever roller 163 to hold the poppet valve 143 in the open position shown in Figures 4 and 5 so that liquid may move freely between the plunger chamber 130 and the reservoir 136.

10 Similarly, should a bottle be of less than the standard height, the plunger spring 132 will act through plunger 131 to hold the cam 120 in such position as to force or hold the mouth of the bottle into close contact with the undersurface of the cap blank C, the upper surface of the latter of course being in close contact with the undersurface of the presser foot 72. In other words, regardless of whether the bottle is of standard height, its mouth will be held closely against the cap blank C at the time that the platform roller 26 is moving over the level dwell 120c of cam 120. The entire effect of the above mechanism is therefore to insure that every bottle, just prior to any action of the capping head, is in close contact with, or is compensated with respect to, the presser foot 72 and the cap blank carried beneath the same.

Continuing, as a bottle supporting platform roller 26 moves over the further portion of dwell 120c, the upright 44 of the preceding bottle platform 25, acting as a trip, will move from the trip lever roller 163 with the result that the valve spring 152 will be free to move the poppet valve 143 to closed position upon its seat 144. Hence 30 the fluid which is in the plunger chamber 130 at this instant will be locked in the chamber so that neither the plunger 131 nor the cam 120 can move downwardly. Immediately thereafter, the roller 26 will move upon the crowning rise 120d of cam 120. This rise will cause the bottle platform 25 to be moved further upwardly, forcing the bottle B from the position shown in Figure 10 to the position indicated at position C in Figure 9 so that the mouth of the bottle will move upwardly within the throat ring 71 and the cap blank C will be properly molded upon the mouth of the bottle. Downward movement of the roller 26 from crowning rise 120d will cause the bottle platform 25 to lower. The roller 26 will then move down the 40 cam decline 120e so that the platform 25 will further be lowered as shown in Figure 3. Almost simultaneously with the movement of the roller 26 past the extreme high point of the crowning rise 120d, the lower end of upright 44, or the corresponding cam surface, will contact with roller 163 of trip lever 160 so that the poppet valve 143 will be moved to open position in readiness for compensation of the bottle upon the succeeding platform 25.

As stated in the above-mentioned Patent No. 2,260,349 for Capping mechanism, when the capping head is raised to the extreme upper position shown in position C of Figure 9, the roller 110 at the upper portion of the capping head will 50 ride upon the cam 111 on the upper portion of the capping structure so that the capping head will be held in elevated position for a short time and while the bottle is moved downwardly to a position slightly below that shown in position C. In other words, the capping head will be held raised until the mouth of the bottle has cleared the cap supporting ledge 96 so that a cap blank may be moved upon this ledge when the capping head subsequently descends as is heretofore explained and as it also described in the patent to

Huntley and Rau No. 1,956,218 referred to above.

The bottle supporting platforms 25 and the rollers 26 associated therewith are intended to move downwardly due to the weight of the platform and the bottle thereon, but should a platform 25 and its roller 26 fail to move downwardly along the cam 120, the roller 26 will contact with an upper fixed cam 175 shown in Figure 4 and which cam is of such conformation that it will cause the platform to be moved downwardly to be flush with the mechanism, not shown, for removing bottles from the bottle supporting platforms 25, just as would occur if the roller 26 were to properly move downwardly along cam 120 to the outfeed end 120f of the cam.

It will be observed from the foregoing that the present compensating structure not only fully and accurately compensate each bottle, but also performs such compensation in such a manner that every bottle will be in firm contact with the capping elements before any capping stroke occurs. In other words, because compensation occurs before capping, it will not be possible for a capping head to suddenly and forcefully come into contact with a bottle mouth, since every movement of both the bottle and the capping head is controlled by carefully designed cams and other positive control elements.

The terminology used in the specification is for purposes of description, the scope of the invention being indicated by the following claims.

We claim:

1. The combination in a container sealing mechanism, of a supporting element having a vertically extending socket therein, a closure applying element seated in said socket against vertical movement, and vertically extending slip-fitting members to hold said closure applying element in said socket.

2. The combination in a container sealing mechanism of a supporting element including a vertically extending side wall and horizontal upper and lower walls, said vertical wall having a laterally facing and open-ended socket therein, a capping element positioned in said socket, said element including laterally extending flanges bearing on the upper and lower walls of said supporting element, said flanges and said supporting elements having aligned apertures therein, and pin elements positioned in said apertures.

3. The combination in a container sealing apparatus, of a rotary table element, a plurality of container sealing devices circumferentially spaced about said table element, each of said devices comprising a capping element and a container supporting element in alignment therewith, means to rotate said table element, compressible means to move one element of one of said devices with respect to the other element of said device to bring the mouth of a container carried by the container supporting element of that device into contact with a cap carried by the corresponding capping element, means actuated by the preceding device to render said compressible means immovable, and means to subsequently move one element of said first-named device further toward the other element of said first-named device to cause the cap to be secured to the mouth of the container.

4. The combination in a container sealing apparatus, of a rotary table element, a plurality of container sealing devices circumferentially spaced about said table element, each of said de-

vices comprising a capping element and a container supporting element in alignment therewith, means to rotate said table element, fluid pressure controlled means to move one element of one of said devices with respect to the other element of said device to bring the mouth of a container carried by the container supporting element of that device into contact with a cap carried by the corresponding capping element, means actuated by the preceding device to render said fluid pressure controlled means immovable, and means to subsequently move one element of said first-named device further toward the other element of said first-named device to cause the cap to be secured to the mouth of the container.

5. The combination in a container sealing apparatus, of a rotary table element, a plurality of container sealing devices circumferentially spaced about said table element, each of said devices comprising a capping element and a container supporting element in alignment therewith, means to rotate said table element, a movable cam positioned in the path of travel of said devices, compressible means to urge said cam upwardly to move a container supporting element upwardly, and trip means carried by said table element and acting to then render said compressible means rigid to hold said cam immovable, said cam including a rise adapted to be subsequently engaged by the container supporting element.

6. The combination in a container sealing apparatus, of a rotary table element, a plurality of container sealing devices circumferentially spaced about said table element, each of said devices comprising a capping element and a container supporting element in alignment therewith, means to rotate said table element, compressible means to move one element of one of said devices with respect to the other element of said device to bring the mouth of a container carried by the container supporting element of that device into contact with a cap carried by the corresponding capping element, trip means carried by said table element and acting to render said compressible means immovable, and means to subsequently move one element of said first-named device further toward the other element of said first-named device to cause the cap to be secured to the mouth of the container.

7. The combination in a container sealing apparatus, of a base, a table element rotatable on said base, a plurality of container sealing devices circumferentially spaced about said table element, each of said devices comprising a capping element and a container supporting element in alignment therewith, means to rotate said table element, a cam track of arcuate form beneath said table and pivoted at its ends to said base, said cam being adapted to lie in a substantially horizontal plane and being positioned in the path of travel of said devices, compressible means to urge said cam track toward said devices to move a container supporting element toward the corresponding capping element, and trip means carried by said table element and acting to then render said compressible means rigid to hold said cam track immovable, said cam track including a rise adapted to be subsequently engaged by the container supporting element.
